UNITED STATES PATENT OFFICE.

GEORGE HARVEY ROBERTS, OF OQUAWKA, ILLINOIS, ASSIGNOR OF ONE-HALF TO
LENARD SCHELL, OF OQUAWKA, ILLINOIS.

ENGINE.

Application filed July 9, 1925. Serial No. 42,511.

This invention aims to provide a novel engine wherein a hollow piston reciprocates within a cylinder and about an abutment which is fixed within the piston and within the cylinder.

It is within the province of the disclosure to improve generally and to enhance the utility of devices of that type to which the invention appertains.

10 With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

20 In the accompanying drawings:—

Figure 1 shows in top plan, a device constructed in accordance with the invention; Figures 2, 3 and 4 are sections taken, respectively, on the lines 2—2, 3—3 and 4—4 of Figure 1; Figure 5 is a longitudinal section wherein parts appear in elevation, the view being diagrammatic, since as many parts as possible have been brought into one plane.

The engine forming the subject matter of this application comprises a cylinder 1. Within the cylinder 1 is located a fixed abutment 2. By-pass pipes 3 and 4 are provided. The inner ends of the by-pass pipes 3 and 4 are connected to the cylinder 1 and to the abutment 2. In this way, the abutment 2 is held in place. The outer ends of the by-pass pipes 3 and 4 are connected to the cylinder 1 and communicate with the cylinder 1 at the ends of the cylinder. The by-pass pipe 3 communicates with a channel 5 in the abutment 2. The channel 5 extends from the side of the abutment, to one end of the abutment. The by-pass pipe 4 communicates with a channel 6 in the abutment 2. The channel 6 extends from the side of the abutment to the end of the abutment. A spring-operated valve 7 is carried by the abutment 2 at one end thereof and controls the channel 5. A spring-operated valve 8 is located at the other end of the abutment 2 and controls the channel 6. There is a valve 9 at the place where the by-pass pipe 4 communicates with the cylinder 1. The

valve 9 opens outwardly. There is a valve 10 at the place where the by-pass pipe 3 communicates with the cylinder. The valve 10 opens outwardly. The cylinder 1 is provided with openings 11 and 12. A spark plug 14 is mounted in the opening 11. A spark plug 15 is mounted in the opening 12. The numeral 16 designates a carburetor. A pipe 17 leads from the carburetor 16 to one end of the cylinder 1. A pipe 18 leads from the carburetor 16 to the other end of the cylinder 1. There is a valve 19 at the place where the pipe 18 joins the cylinder 1. The valve 19 opens inwardly. There is a valve 20 at the place where the pipe 17 joins the cylinder 1. The valve 20 opens inwardly.

The numeral 21 designates a hollow piston. The abutment 2 is located within the piston 21 and the piston reciprocates between the abutment and the cylinder 1. The piston 21 is closed at its ends. The piston 21 is provided at one end with a rod 22 working in a gland 23 on the corresponding end of the cylinder 1. There are elongated slots 24 in the piston 21. The slots 24 receive the inner ends of the by-pass pipes 3 and 4, so that the piston can reciprocate with respect to the abutment 2. The piston 21 carries packing rings 25 cooperating with the cylinder 1. The abutment 2 has packing rings 26 cooperating with the piston 21. The cylinder 1 is supplied with exhaust ports 27 and 28. The exhaust ports 27 and 28 communicate with an exhaust pipe 29. The piston 21 has exhaust ports 30 and 31. The exhaust port 30 of the piston 21 is adapted to communicate with the exhaust port 27 of the cylinder 1. The exhaust port 31 of the piston 21 is adapted to communicate with the exhaust port 28 of the cylinder 1. The piston 21 is provided near to its ends with firing ports 32 and 33. The firing port 32 is adapted to register with the spark plug opening 12 in the cylinder 1. The firing port 33 is adapted to register with the spark plug opening 11 of the cylinder 1.

When the piston 21 moves to the left in Figure 5, the charge is sucked into the right end of the cylinder through the pipe 18, the valve 19 opening, and the valve 9 closing. When the piston 21 moves to the right, the valve 19 closes, the valve 9 opens, the valve 8 opens, and the charge passes from the right end of the cylinder 1 through the

pipe 4 and the channel 6 into the left hand end of the piston 21 and is compressed. By the time that the piston 21 moves to the end of its compression stroke, the port 32 registers with the port 12 and the charge is fired, the piston 21 moving to the left, and the exhaust leaving through the registering ports 30 and 27. The operation has been traced out from the right hand end of the cylinder 1, but it will be understood, without further description, what takes place when the charge enters at the left hand end of the cylinder, by way of the pipe 17.

A receptacle 34 is mounted on the cylinder 1, and communicates through an opening 35 with the water jacket 36 of the cylinder 1. As shown at 37, the inner wall of the cylinder 1, the piston 21 and the abutment 2 have registering openings 37 by which water can circulate through the hollow abutment 2, about the channels 5 and 6.

I claim:—

1. In an internal combustion engine, a cylinder, an abutment fixed within the cylinder, a piston mounted for right line reciprocation within the cylinder and around the abutment, the abutment having channels leading from its sides to its ends, valves

on the abutment at the ends of the channels, by-passes leading from the ends of the cylinder to the sides of the abutment and communicating with the channels, valves controlling the by-passes, means for exhausting the spaces within the piston at the ends of the abutment, and means for firing charges in said spaces.

2. In an internal combustion engine, a cylinder, an abutment fixed within the cylinder, a piston mounted for right-line reciprocation within the cylinder and around the abutment, the abutment having channels leading from its sides to its ends, by-passes leading from the ends of the cylinder to the sides of the abutment and communicating with the channels, valves controlling the by-passes, means for exhausting the spaces within the piston at the ends of the abutment, means for firing charges in the said spaces, inwardly closing valves carried by the abutment and controlling the channels, and spring means for seating the last-specified valves.

In testimony that I claim the foregoing as my own, I have hereto affixed my signature.

GEORGE HARVEY ROBERTS.
